UNITED STATES PATENT OFFICE.

GHEEN R. ABBOTT, OF BALTIMORE, MARYLAND.

MOLD FOR CONSTRUCTING CONCRETE TUNNELS.

1,137,442.

Specification of Letters Patent. Patented Apr. 27, 1915.

Application filed May 8, 1914. Serial No. 837,122.

To all whom it may concern:

Be it known that I, GHEEN R. ABBOTT, a citizen of the United States, residing at Baltimore, in the State of Maryland, have 5 invented certain new and useful Improvements in Molds for Constructing Concrete Tunnels, of which the following is a specification.

This invention relates to collapsible molds 10 or centers for the formation of tunnels for conduits, sewers, and other earth-covered structures.

One object of my invention is to provide 15 an improved construction of a cylindric, or part-cylindric mold of light metal for use in forming concrete or cement earth-covered conduits, whether formed by tunneling or in a ditch and then covered.

The improved mold is illustrated in the 20 accompanying drawing in which,—

Figure 1 is a cross-section of a conduit, and a mold-section within the conduit—the single arch-rib angle-bar at the end of the section being shown. The base is made 25 of brick and the arch of concrete. Fig. 2 is a top plan of a portion of mold used in tunneling, and shows the door or key that closes the top-opening in the mold. Fig. 3 is a 30 vertical longitudinal section of the part-cylindric mold taken on the line 3—3 of Fig. 1; this figure shows one half of one mold section. Fig. 4 shows a cross section on line 4—4 of Fig. 3, showing the key-plate that closes the top-opening. Fig. 5 35 shows the single arch-rib at the top-opening, and illustrates the supplemental piece of rib that is added to span across said top-opening. Fig. 6 is a perspective view of the 40 intersection and joiner of one arch-rib and one straight longitudinal connecting angle-bar. Fig. 7 is a view of an end-coupling of one of the turn-buckle rods. Fig. 8 is a view 45 of part of the trap door or key. Fig. 9 shows a detail of one journal bracket, and Fig. 10 is a cross-section of a cylindric mold of a 50 conduit which in this instance is made wholly of concrete, and showing the rods used for collapsing the mold.

Referring to the drawing Fig. 1 shows 55 a cross-section of a cylindric conduit in which the invert, 9, is made of brick resting on a foundation, 10, of concrete, and the

arch, 11, rests on the said brick invert. In forming a conduit of this construction I use a part-cylindric mold, 14, which should be 55 made in sections of a length convenient to handle. To afford support for the part-cylindric mold, I use cross-ties, 12, with undercut beveled ends, 13, which rest on the sloping surface of the brick-work of the invert, 9. The cross-ties at the bottom of the conduit may form a cover, approximately, for two sevenths of the interior cylindric surface of the conduit, that is, a cover over the brick invert, 9, thereby the part-cylindric mold, 14, would extend over about five sevenths of said interior surface of the conduit comprising the arch, 11. Two pairs of wood stringers are supported on the cross-ties, 12. One pair, 15, at the center (Fig. 70 1) serves to support the iron rails, 16, that constitute the car-track; and the other pair of stringers, 17, are traversed by the rollers, 18, hereinafter described, that serve to move a section of the part-cylindric mold. The 75 said part-cylindric mold is shown in Figs. 1 and 3, and comprises a series of arch-ribs, 19, each formed of two curved angle-bars; these two bars are placed together in contact side by side and form a T in cross section, so that the outer or convex curved surface, 20, of the two bars will be flush with each other and constitute the top cross of the T and the outer sheet-metal shell, 24, rests 80 on said part, 20. The sides of the two 85 curved angle-bars that are in contact, are fastened together by rivets, 21. Straight horizontal angle-bars, 22, connect the several arch-ribs of each mold-section.

The mechanical construction for effecting 90 the intersection and joiner of an arch rib, 19, and a straight double angle bar, 22, is shown in Figs. 3 and 6; one side of each straight angle bar contacts with the other and the two are fastened together by rivets, 95 23; in cross-section these double horizontal bars form a T, the cross or top, 22, of which is the part that contacts with the cylindric shell 24, of the mold. The vertical arch-ribs, 19, have no notch or break at their 100 intersection with the straight horizontal bars, 22, but that part of the latter that has the rivets, 23, is cut cross-wise, and the portion between the cuts is removed and each

- cut forms two ends, 25, between which is the said vertical arch-rib, 19. The horizontal bar, 22, is fastened to the vertical rib, 19, by a short arm, 26, that is integral with the bar, 22, and laps over the base-part, 20, of the vertical rib, and the extremity of said short arm is bent at a right-angle, 28, and contacts with said rib, 19, and is secured thereto by a rivet, as seen in Fig. 6.
- 10 Special provision is made for moving one section of a part-cylindric mold, 14, forward after the concrete, that has been supported by that mold, has hardened and set; the means for such moving comprises rollers, 18, that travel on the wood stringers, 17. Each roller, 18, turns on a journal arm, 29, which is provided at one end with a bracket-base, 30, that is secured to the lower part of the metal shell, 24; the journal arm 20 projects horizontally. In Fig. 3 the part cylindric mold-section has two rollers, 18, one being near each end. Of course, the other half of the same mold-section, not seen in Fig. 3, also has two rollers.
- 15 By reference to Fig. 1, a narrow space, 31, will be seen between the top surface of the cross-tie, 12, and the lowermost part of the arch-rib, 34, at opposite sides of the conduit; this space indicates that the lower 20 end of the arch-rib does not seat or rest on the cross-ties, 12. It will be understood, therefore, that the mold-section, 14, is supported by the projecting journal arms, 29, and rollers, 18, resting on the stringers, 17.
- 25 A wedge 39, has position on top of the cross-tie 12, and its point end in the direction of the nearest side wall is entered below the roller-stringer 17; two wedges, one used at each opposite side, serve to crowd 30 the parts of the mold-section upward at the time the mold is being placed in position. When the mold is about to be removed from the concrete, the wedges serve to aid in loosening the mold-section from the concrete 35 by their withdrawal from below the stringer 17, which causes the stringer to tilt down with the effect that the top of the mold-section will release from the concrete; finally on tightening the turn-buckle 33, the entire side walls of the mold will loosen from the concrete.
- 40 Referring to Fig. 3, the letters A—B designate the two ends of a mold-section, 14, which may be of any convenient length. The center arch-rib, 19, comprises two angle-bars, but each end of this mold-section terminates with an arch-rib consisting of only one angle-bar, 34. The end of another mold-section, C, immediately adjoins the 45 mold-section, 14, and said end has a single angle-bar, 35, and these two angle-bars, 34—35, constituting the ends of abutting mold-sections, are temporarily secured together by bolts, 36, each bolt being held in place by a cotter-pin, 37, instead of screw-

threads. In the present instance, the mold-section from A to B, as shown in Fig. 3, has one double bar arch-rib, 19, between the single angle-bar ribs, 34, at each end of said section. Of course, more than one double arch-rib may be used between the ends where the greater length of the mold-section renders more than one rib advisable.

50 A rod, 32, see Fig. 1, extends cross-wise of the conduit or the mold, and below the track rails, 16, and the ends of this rod connect with the two lower parts of the arch-rib, 34. This rod has a turn-buckle, 33, by means of which the rod may be lengthened or shortened, and thereby the lower parts of 55 the arch-rib at opposite sides of the conduit be spread apart or drawn together. The cross-rod, 32, is below the track-rails, and passes through notches cut in the top 60 surface of the stringer, 16.

55 At the top and center of the mold-section, 14, is an opening that extends longitudinally from one end to the other of the mold-section, and this opening is closed by a trap-door or key, 38, see Figs. 1, 2 and 4. This opening enables the workmen who must stand within the mold, to handle the wet mixture of concrete, and pass it from the inside of the mold through said top-opening to the outer side to form the top of the arch 65 11, at the two sides of the opening and close to the parallel stringers 43, along opposite edges of the longitudinal opening; thus the part of the arch remaining unfilled will be only the longitudinal central top part, or 70 keystone part, where said opening is. When this work of placing the wet concrete on top of the mold as far as the said stringers 43, has been done, the workmen inside of the mold will place the trap-door 38, in position 75 and thereby close said opening. The workmen will then stand at the forward or unconnected end of the mold-section, and pass the wet concrete up over said end, and place it on top of the closed trap-door 38, and by 80 using a suitable implement will push and ram such concrete back along the upper surface of the trap-door until the space over the entire length of said trap-door, and corresponding to a keynote, has been well filled. 85

90 To permit the single arch-rib 34, shown in Fig. 1, to slightly tilt toward the center when preparing to remove the mold, it is preferable to remove the supplemental piece of rib 40, that spans across the end of the 95 top-opening that is closed by the trap-door 38; the two projecting ends 48, of this trap-door rest on said rib-piece, and by removing the latter the said trap-door itself may be withdrawn, and thereby aid in collapsing 100 the mold. The supplemental rib piece 40, has beveled ends, see Fig. 5, that fit corresponding beveled top ends of said single arch-rib 34, which is at the end of each mold-section. Said supplemental rib-piece 40, is held in its 105 110

position by over-lapping plates 41, that couple the ends of the supplemental piece to the top ends of said arch-rib 34. By removing pins 42, from the over-lapping plates 41, the supplemental rib-pieces 40, may be entirely detached, and then the arch-ribs 34, at the opposite sides of the mold-section, may be loosened from the concrete wall, and slightly tilted.

- 10 The dotted curved lines in Fig. 1, are intended merely to illustrate the idea, or the direction of tilting the two opposite sides of the mold-section; in practice the extent of this inward tilting would generally be 15 slight, sometimes as little as a half-inch— enough however to release the mold from adhering to the concrete wall.

It is to be understood this description of the supplemental rib-piece, 40, and the means 20 of its attachment at one end of a mold-section, is applicable to the opposite end of the same mold-section. Furthermore, it is to be understood such a rib-piece, 40, is also applicable to the next mold-sections, 35, whose 25 ends adjoin or abut against either of the single arch-ribs, 34, of the mold-section, 14, which has just been described.

In order to strengthen the mold-section along the top and center where the longitudinal opening is, I place two parallel angle-bar stringers, 43, which extend along the top of the arch from the single arch-rib, 34, at one end of the mold-section to the single arch-rib, 34, at the opposite end; the 35 top ends of the middle arch-rib, 19, abut against said stringers, 43, and the down-flange of said angle-bar stringer has a number of short slots, 44. Said two parallel angle-bar stringers are spaced apart from 40 each other to form the top-opening, and the two parallel down-flanges, 45, on the under side and along the two longitudinal edges of the trap-door or key, 38, fit between said two parallel stringers, 43, and when the 45 trap-door is closed, pins, 46, are inserted through the holes in said down flanges, 45, of the trap-door, and also through the slots, 44, in the stringer, 43, as shown in Fig. 4. The door also has on its under side, and 50 crosswise near each of its ends, a shorter angle-bar, 47, forming a down-flange that extends crosswise of the door; the cross-flange, 47, is far enough from the extreme end of the door for said end to form a horizontal projection, 48, see Fig. 8. The projecting end, 48, of the door rests on the top 55 of the supplemental rib-piece, 40.

The description thus far is more particularly related to the form of mold-section, 60 that is part-cylindric, as shown in Fig. 1, though much of said description is also applicable to the fully-cylindric form shown in Fig. 10. In Fig. 10 the mold-section shown has the form of a complete cylinder; 65 it has the same top-opening and trap-door

or key, 38, the vertical arch-ribs are the same, except those in Fig. 10, form a complete circle, and the horizontal bars, 32, are also the same. The structure in Fig. 10, permits the removal of the over lapping 70 plates, 41, of the top parts of arch-rib 19, so that both sides of the mold may tilt toward the center, for the purpose of collapsing. In Fig. 10, two cross-rods, 49, are shown connecting with opposite sides of the arch-rib, 75 19; each rod has a turn-buckle, 50, that screws on the rod and enables the rod to be lengthened or shortened. To collapse, these rods must be shortened or removed.

It is to be understood that either the form 80 of structure shown in Fig. 1, or the form shown in Fig. 10, may be used for constructing concrete conduits in a ditch which when finished is to be covered with earth.

Having thus described my invention, what 85 I claim and desire to secure by Letters Patent is—

1. A mold-section for the formation of concrete tunnels having in combination two vertical arch-ribs 34, at each end of the 90 mold-section; two parallel stringer bars 43, extending from the top ends of said two ribs at one end of the mold-section to the like ends of the two ribs at the other end, and said two parallel stringer bars spaced apart 95 and forming between the two an opening along the entire top of the mold-section; a supplemental rib-piece 40, spanning across each end of said top opening and attached to the said top ends of the vertical arch-ribs; a horizontal cylindric sheet-metal shell 100 around said arch-ribs and at the top said shell having two longitudinal edges each of which is attached to a different one of said two stringer bars; and a trap-door having a 105 down-flange along both longitudinal edges and fitting within said top opening and said door provided at its ends with horizontal projections which rest on said supplemental rib-pieces. 110

2. A mold-section for the formation of concrete tunnels having in combination a vertical arch-rib at the two opposite ends of the section; a double vertical angle-bar arch-rib 19, intermediate said ribs at the 115 two ends; a double horizontal angle-bar 22, intersecting said vertical intermediate angle-bar arch-rib, and joined therewith by a short arm 26, that is integral with said horizontal bar and lapping over a part of 120 said vertical arch-rib and the extremity of said short arm bent at an angle 28, and riveted to said rib, and a cylindric sheet-metal shell covering all said arch-ribs and horizontal bars. 125

3. A part-cylindric mold-section for the formation of concrete tunnels having in combination cross-ties supporting two stringers each adjacent to an opposite side of the mold-section and extending parallel 130

with said side; wedges between the cross-ties and the lower surface of said stringers—the thin edge of each wedge pointing to the nearest side of the conduit and the 5 large end of each wedge being nearer the center of the conduit; a part-cylindric mold arched over said cross-ties and stringers, the lower part of both sides of said mold provided with arms 29, projecting over said

stringers and means on the said projecting 10 arms that rest on said stringers.

In testimony whereof I affix my signature in presence of two witnesses.

GHEEN R. ABBOTT.
